CASE SHIFT MECHANISM FOR
TYPEWRITING MACHINES

John C. Veltman and William O. Michelsen, St. Louis County, Mo., assignors to The Emerson Electric Mfg. Co., St. Louis, Mo., a corporation of Missouri

Application August 27, 1945, Serial No. 612,772

10 Claims. (Cl. 197—73)

1

This invention relates to typewriters.

A primary object of the invention is the provision of an improved typewriting machine, having a platen carriage, and segment and type bar assembly which are relatively and simultaneously shiftable, whereby the upper and lower case type are selectively positioned to strike the platen on the printing line.

A further object is to construct a machine of this type in such a manner as to provide a balanced shifting device, whereby positioning the segment and type bar assembly, and the platen carriage for double case printing may be effected with a minimum of movement and a minimum of application of force, whereby wear upon and distortion of parts is substantially avoided.

More specifically an object is to cooperatively support and connect the platen carriage, and segment and type bar assembly in a weight balanced relation, in order that applied force in accomplishing the shifting operation is substantially reduced, resulting in an extremely light shift key action.

Another more specific object is to reduce the movement necessary in effecting relative shift of the platen carriage, and segment and type bar assembly, which results in reducing the inertia of the moving parts, thereby reducing impact on the parts on termination of movement, and thereby minimizing the noise of operation and wear on the parts as a result of impact at the end of the shift movement.

Another object of the invention is to embody in a typewriting machine having the foregoing characteristics an efficient shift mechanism for the platen carriage, and segment and type bar assembly, which operates the shift with facility and holds the same in proper adjustment for upper and lower case printing, said shift mechanism having lock devices, which are particularly adapted for such purpose.

Another object of the invention is the provision of a type bar operating means that is particularly adapted for quiet and efficient operation, particularly in combination with the character of shift mechanism above specified.

Additional advantages of the invention will appear from the following detailed description of the invention taken in connection with the accompanying drawings, in which:

Fig. 1 is a skeletonized isometric view of such parts of a typewriting machine as are essential to illustrate the embodiment of the invention, particularly with respect to the type action and relative platen carriage, and segment and type

2

bar assembly shift. In this view the parts are shown in initial position;

Fig. 2 is a similar isometric view further skeletonized to further illustrate essential parts in printing position;

Fig. 3 is a view of certain essential parts of the shift mechanism for shifting the platen carriage, and segment and type bar assembly, and also the upper and lower case locks;

Fig. 4 is a view similar to Fig. 3, in which the parts shown therein are in association with co-operating parts of the printing mechanism;

Fig. 5 illustrates essential parts of the printing mechanism, particularly the key action; and

Fig. 6 is a detail of the stop associated with the universal bar.

As illustrated in the drawings, the machine embodying the invention is shown as including a skeleton frame to be mounted in a conventional manner in a main frame (not shown). The skeleton frame comprises right and left side frame members 1 and 2, with provision in the form of spaced openings 3 for mounting and attaching said skeleton frame in the main frame 20 of the machine.

The segment and type bar assembly, and the platen carriage assembly are each pivotally mounted between said frame members 1 and 2, the former by pivot mountings at 4, adjacent to the front of the machine, and the latter by pivot mountings at 5 adjacent to the rear of the machine.

The general structure of the segment and type bar assembly is best shown in Fig. 2, from which it will appear that, as illustrated, it comprises a segment 6 supported on a transverse plate 7, which extends laterally to each side of the machine. The extremities of the plate 7 are bent to form right angle forwardly extending sections 8, each of which is removably connected with a forwardly extending arm 9, which arm pivots on the respective frame members 1 and 2 on the pivot member 4.

The lower rail assembly of the platen carriage 45 comprises bracket members 10, which are cross connected by a tube 11.

A convenient means of securing the extremities of said tube 11 to the brackets 10 comprises, as illustrated, plugs 12 inserted through openings in 50 the respective brackets 10, said plugs being inserted into the openings in the opposite ends of the tube 11, and then forming a rigid joint by brazing or welding these parts together. The plugs 12 may be drilled and countersunk to form 55 bearings for pivot screws 13, which are locked by

nuts 14 in the side members 1 and 2 of the frame, and which screws, therefore, constitute the pivot mountings for said tube 11, which, in turn, serve as the rocking or pivot supports 5 for the platen carriage assembly.

A lower rail 15 extends transversely of the machine. This rail constitutes the support for the platen carriage, it being understood that said carriage is shiftable transversely thereon in the usual manner. This lower rail rests upon and is secured to brackets 16 positioned adjacent to each end of said rail. The brackets 16, in turn, are releasably and adjustably secured to the top wall of the respective brackets 10, preferably by screws 17 that pass through elongated slots 18 in angular extensions 19 of the brackets 16, which screws thread into openings in said top wall of each of the brackets 10, as best illustrated in Fig. 2. Since, therefore, the lower rail assembly and the shiftable platen carriage carried thereby are rigid with said brackets 10, which, in turn, are pivotally mounted on the pivot screws 13 rigid with the frame, the entire platen carriage support is assembled for rocking movement in respect to the frame of the machine. As will be later explained, the rocking movement of the platen carriage assembly from its normal position of rest is in an arcuate direction opposite from the movement of the segment and type bar assembly in shifting to and from the upper and lower case printing positions.

The platen carriage assembly, and the segment and type bar assembly are pivotally interconnected at each side by rocking arms 20. The arms 20 are connected with the respective brackets 10, at their rear extremities, by screw and slot connections 21 and, at their front extremities, are connected by a screw and slot connection 22 with the plates 9, which constitute the pivoted arms by which the segment and type bar assembly is supported. The arms 20 constitute rocking arms or levers, having a pivot connection intermediate their extremities with the respective side members 1 and 2 of the frame. A pivot screw 23 passing through each frame member and through each of said arms serves to permit the relative rocking movement of said arms in respect of the frame, and thereby a rocking counterbalanced connection between the segment and type bar assembly, and the platen carriage assembly.

In order to provide for proper alignment and adjustment between the right and left hand rocking connection between these two assemblies to compensate for any misalignment or distortion in either of them, it is preferable to form one of said arms in two sections, as illustrated, and to join said sections by a dowel, slot and screw connection 24 arranged so that a slight angular adjustment between the two sections of the arm may be made.

The segment and type bar assembly is normally held in raised position by a pair of springs 25, the upper ends of which are adjustably supported in a stationary part of the machine (not shown), and the lower ends are connected, respectively, with the rear section of the plates or arms 9 of the segment and type bar assembly frame. These springs serve to resiliently hold said plates in such angular position that the forward ends of the rocker arms 20 are raised, thereby tilting the platen carriage assembly forwardly and downwardly, and the segment and

type bar assembly backwardly and upwardly (Fig. 1).

In order to limit the extent of the relative up and down movements of the segment and type bar assembly, and the platen carriage assembly, shift motion stops are provided which, as illustrated, include a pair of parallel spaced arms 26 secured to the segment plate 7 adjacent to each end thereof, which cooperate with arms 27, one of which is attached adjacent to each end of the carriage frame in a position to extend through openings in the plate 7 and between said arms 26. The arms 26 are formed of material which may be slightly flexed so that said arms may be adjusted by bending to adjust the limit of the shift movement either up or down, whereby the relative movement of the segment and type bar assembly, and of the platen carriage assembly will be brought to rest for proper alignment of the printing line of the platen for either upper or lower case printing.

A series of type bars 28 are pivotally mounted in and supported by the segment 6 in conventional arrangement. The type bars take the form of bell crank levers and are preferably pivotally supported on a wire 29 seated in a slot formed in the periphery of the segment 6.

It will be understood that the number of type bars 28 preferably includes the usual number from forty-two to forty-six, in order to provide for the usual complement of printing characters arranged on the face of the type 30 in upper and lower case arrangement.

The segment 6 is provided with the usual spacing walls 31 forming slots that guide the individual type bars.

In the drawings, only sufficient of the type bars have been illustrated to disclose the arrangement thereof in relation to the structure of the present invention.

The key levers 32 for operating the type bars are supported in a key lever bracket 33, which is supported transversely of the machine, and is rigidly connected at its extremities to the inner faces, respectively, of the plates 9 constituting the side members of the frame of the segment and type bar assembly, whereby the type bars and their operating means move as a unit in shifting movements.

A series of spaced key lever guides 34 in the form of bifurcated lugs form slots in which the inner ends of the key levers 32 are seated. The inner ends of the key levers 32 are pivoted on a rod 35 passing through openings in the levers 34 and seated between the aligned arms of the members 36. A comb 36 is positioned forwardly of the bracket 33, which comb is also supported at its extremities by the plates or arms 9. This comb 36 has a series of vertical slots extending from its bottom edge through which the key levers 32 extend and are guided thereby.

A series of intermediate bell crank levers 37 are carried by and pivoted upon a rod 38 supported in the lower section of the key lever bracket 33. A series of spaced slots 39 extend upwardly from the bottom of said bracket and constitute guides in which said levers 37 rock.

Each of the key levers 32 is formed with an angular arm 32' that extends downwardly and rearwardly, the tip of which projects into the respective slot 39 and contacts the depending arm of its respective cooperative intermediate bell crank lever 37 when the selected key lever is operated.

The rear arm 40 of each of the intermediate

bell crank levers 37 is connected with its complementary type bar by a wire link 41.

The type levers and key levers are held in position of rest (Fig. 1) by a spring 42 attached at one end to the forward arm of each of said intermediate bell cranks and at the other end to brackets 43 attached to said key lever bracket 33. The tension of the springs 42 also serves, by exerting pressure on the front edge of the depending arms of the intermediate bell cranks against the depending arms of the key levers, to hold the key levers against a cushion strip 44 supported on the back face of the vertical wall of the comb 36 above the slots formed therein, which strips cushion the rebound of the key levers.

By arranging the ends of the link connection between the intermediate bell cranks and the type levers in line with the pivot point of said bell cranks, a toggle effect is provided that serves to lock the type bars in their position of rest, and also to prevent rebound of and interference between the type bars.

The mechanism for effecting the relative shift of the segment and type bar assembly, and the platen carriage includes shift key levers 45 and 46 positioned, respectively, at the right and left of the key board. The rear ends of said levers are connected by a transverse tie tube 47. The levers 45 and 46 are normally held in raised position by a pair of springs 45' and 46' attached, respectively, at one end to said levers 45 and 46, respectively, and, at their opposite ends, to the top wall of the comb 36. The top edge of each of said levers also cushions against the extremities of the cushion strip 44.

The depression of either shift key lever 45 or 46 rocks the shift frame comprising said levers and the tie tube 47, and, through linkage with the arms 20, lowers the front ends thereof and raises the rear ends, thereby moving the segment and type bar assembly downwardly, and raising the platen carriage assembly to shift the printing line of the type on the platen.

The means whereby the movement of the shift key levers is translated to this rocking movement of the arms 20 include a pair of cushion levers, one of which is cooperatively associated with each of the shift key levers 45 and 46. These cushion levers take the form best shown in Figs. 3 and 4, from which it will appear that said levers each include arms 48 and 49 forming a bell crank lever pivoted at 50 to one face of vertical arms 51 formed on each of the levers 45 and 46 at the rear extremities thereof. The cushion members each have a third arm indicated at 52, the extremity of which is bent at an angle to form an ear 53 which overlies the top edge of its respective shift lever 45 and 46. The lower extremity of each of the arms 48 is spring connected to the lower end of said vertical arms 51 by a spring 54. Each ear 53 overlies the upper edge of its respective associated shift lever and opposes the contraction of the springs 54. Upon downward movement of either of said shift levers 45 or 46, the springs 54 rock the arms 48 rearwardly, or to the left in Fig. 3.

Each of the arms 20, rearward of its pivot, has a depending arm 55. The lower extremities of said arms 55 are each bent inwardly, forming ears 56 which extend into the plane of the arms 49. Therefore, when the bell cranks 48-49 pivot under the influence of the springs 54 on depression of either shift key lever, the rear edges of the arms 49 impinge against the ears 56 causing the arms 20 to rock and thereby impart the dou-

ble shifting movements to the segment and type bar assembly and the platen carriage assembly, as above described.

Since the two shift levers are interconnected, it is only necessary to provide a shift lock associated with one of them. As illustrated, this lock is associated with the left shift key lever and, as shown, comprises a lever 57 pivoted to one side face of the lever 48. The lever 57 is formed with a shoulder or detent at its lower extremity, which engages with a lug 58 which may be attached to a frame brace 58' of the machine. It is preferably made adjustable by being secured thereto by a binding screw. When a shift lock key lever 59, pivoted on the shift lever 46, is depressed, the end of said lever rocks against the tendency of a spring 60, which connects the lower extremity of the lever 57 with the shift key lever. The spring 60 normally keeps the detent disengaged upon the normal depression of the shift key levers, unless the shift lock key 59 is also depressed. After the detent is engaged by depressing the lock key lever 59, the spring 60 also serves to disengage the detent by slight pressure on one of the shift key levers to move it downwardly slightly beyond its normal depressed position. This slight additional depression of a shift key lever to release the detent is possible without any strain on the parts, because the connection between the rear extremity thereof, and the bell crank levers 48-49 for rocking the arms 20 is a resilient connection because of the springs 54. This construction, in effect, provides a cushion connection between the shift key levers and the arms 20, as above explained.

It will be understood that when the shift mechanism is operated as described, the relative positions of the segment and type bar assembly, and platen carriage assembly are reversed from the normal or at rest position. In normal position the segment and type bar assembly is in raised position and the platen carriage is tilted downwardly as already explained. This is the lower case printing position. When the shift occurs the segment and type bar assembly moves downwardly and the carriage platen is raised, thus, by simultaneous movement of the two assemblies, each of which makes approximately one half of the combined movement, the necessary spacing to align the upper case type to the printing line is accomplished. Since the movement of each of the assemblies is only approximately one half of the combined movement to effect the shift, and, since the assemblies counterbalance each other, the inertia of the movement, and impact at the termination of the movement is substantially reduced.

The locking of the assemblies in shifted position, in order to properly align the type for upper case printing, is effected by the shift locking mechanism, as described. It is also preferable that the assemblies be locked in their normal position to prevent any disalignment of printing in the lower case, and this lower case lock must be coordinated with the shift mechanism, so that it may be unlocked when the shift occurs.

The mechanism for effecting the locking of the assemblies in the initial position includes a bell crank lever associated with each of the rocking bars 20. These bell crank levers each include an arm 62, which extends forwardly and downwardly, and an arm 63 in the form as illustrated in Fig. 3 of the drawings. These levers are pivoted at 64 on a pivot support attached, respectively, to the inside face of each of the frame members 1 and 2. The forward extremity of each

of the arms 62 is bent at an angle forming an ear 65, which ears extend into the plane of the ears 56 formed at the extremities of the arms 55 of the rocking bars 20. The arms 62 are normally held in angular adjustment, as illustrated in Fig. 3, in which the ears 65 are in a position to contact with the ears 56, and thereby prevent the rocking of the arms 20 when the parts are in initial position.

The means for maintaining normal adjustment of the arms 62 with the ears 65 in locking engagement with the ears 56 comprises a spring 66, one end of which is attached to the lower extremity of the arm 63, and the other end of which is connected to a spring post carried by the respective one of the side members 1 and 2. It will be understood that this position of the parts is maintained until the shifting mechanism is operated.

When the shifting mechanism is operated by depression of one of the shift keys 45 or 46, an angular link 67 pivoted at 68 to the lower extremity of the respective vertical arms 51 is moved rearwardly. The links 67 assume the angle shape best illustrated in Fig. 3, and are supported and guided in their movements by a screw 69 extending inwardly from each of the side members 1 and 2, respectively, said screws projecting into slots 69' in the upper extremity of the vertical arm of the links 67. The upper rear edges of the links 67 are formed as cam faces 70, which cooperate with fingers 71, which ride on the cam faces 70 in such relation that, when the links 67 are moved rearwardly upon depression of either of the shift key levers, through the linkage just described, the ears 65 of the arms 62 are moved downwardly against the tendency of the springs 66, thereby releasing the locks or detents 56-65, so that the arms 20 are free to rock upon continued movement of the shift key levers. This release of the detents occurs on the initial depressive movement of the shift key levers, and before the rear edge of the arm 49 of the cushion arms contacts the ears 56 to impart rocking movement to the rocker arms 20. This is because of the fact that there is a slight space between said arms 49 and the ears 56, thereby retarding the contact until the arms 62 are moved downwardly sufficiently to clear the ears 65 from the ears 56.

It is preferable that the fingers 71 be made sufficiently flexible in order to adjust their contact tips with the cam faces 70 to regulate the timing of the release of the lock and so that, after it has been released, the tip of the fingers 71 will ride on the cam faces 70 during further depression of the shift key levers, thereby holding the lock out of locking engagement during the period that the shift key lock is operative to hold the assemblies for upper case printing.

The escapement mechanism and the platen carriage is of conventional construction and, therefore, will not be specifically described. The operation of the escapement mechanism, however, includes certain novel features to adapt it to the shift features of the machine.

This operating mechanism includes a universal bar 72 supported transversely of the machine in the rear of the depending arms of the levers 37. The universal bar 72 carries at each extremity an arm 73, which arms are, in turn, pivotally mounted at their upper ends on the rod 38, that supports the intermediate bell crank levers 37. The arms 73 rock in slots formed at the ends of the support for the bank of the levers 37.

Since the universal bar 72 is adjacent to the depending arms of the levers 37, whenever any-

one of them is rocked upon depression of a key lever, the universal bar 72 will be rocked rearwardly. In order to adjust the contact and timing of the contact with said universal bar 72, the depending arms of the levers 37 may be bent to adjust the angular relation of their rear edges to the universal bar.

An adjustable stop limits the return movement of the universal bar 72 when the key lever is released. This stop comprises a bracket 74 carried by each of the arms 73 and positioned to contact the rear face of the key lever bracket when the universal bar is in its initial position. The part of the bracket that makes this contact may carry a cushion 75 in order to reduce the shock and noise of the contact.

An escapement trip push link 76 is pivoted at its rear end at 77 to a conventional escapement mechanism generally indicated at 78. The front end of the link 76 rides in a slot 79 formed in a cross brace. A plate 80 is secured to the top face of the push link 76 to which it is secured in any suitable manner, and an arm 81 formed integrally with said plate extends upwardly at an angle and is located rearwardly of the universal bar 72. The arm 81 is adjusted at an angle, so that the contacting face thereof will remain parallel to the axis of the universal bar in its upper and lower case position.

It will be apparent that upon each depression of a key lever, the universal bar 72 is rocked in a rearward arc contacting the arm 81, and thereby moving the escapement trip push link 76 rearwardly, whereby, in a conventional manner, a step by step movement is imparted to the platen carriage. The angular position of the arm 81, as above explained, is of importance because the universal bar 72 moves as a unit with the segment and type bar assembly and, therefore, whenever a shift is made, the point of contact of the universal bar changes position vertically in respect of the arm 81. This change in relative position of the universal bar and the actuating connection with the escapement push link is compensated for by the adjustment of the angle of the arm 81. Therefore, irrespective of the relative position of the segment and type bar assembly and the platen carriage assembly, the escapement will be tripped at the same point in the movement of the type levers in respect of the platen.

The machine includes the usual spacing bar assembly 82 but, since this is conventional, it is unnecessary to specifically describe its elements.

The construction and operation of an embodiment of the invention will now be apparent from the foregoing description amplified by the accompanying drawings. It will also be obvious that certain modifications from the illustrative embodiment of the invention may be made without departure from the scope and principles of the invention.

Having made full disclosure of the invention, what is claimed is:

1. In a typewriting machine including a platen carriage assembly and a type bar assembly, said assemblies being pivoted for rocking movement in a frame, an interconnection between said assemblies comprising rocking bars pivotally supported on the frame and pivotally connected to each of said assemblies, and a shift mechanism for actuating said rocking bars, whereby said assemblies are moved in opposite arcuate directions for upper and lower case printing positioning of the type bars.

2. In a typewriting machine including a platen carriage and a segment and type bar assembly mounted for upper and lower case printing by movement in opposite directions, an actuator for imparting simultaneous movement to said assemblies, including rocker arms having fixed pivots and a rocking pivot connection with each of said assemblies, respectively, key controlled lever connections for actuating said rocker arms in one direction, and spring means actuating said arms in the opposite direction.

3. In a typewriting machine including a platen carriage and a segment and type bar assembly mounted in weight balanced relation for upper and lower case printing, rocker arms having fixed pivots and a rocking pivot connection with said assemblies, respectively, at opposite extremities thereof, key controlled lever connections for rocking said rocker arms in one direction, and spring means actuating said arms in the opposite direction.

4. In a typewriting machine including a platen carriage and a segment and type bar assembly mounted for movement to upper and lower case printing positions, an actuator for imparting simultaneous movement to said assemblies in opposite directions, including rocker arms having fixed pivots and rocking pivot connections with said assemblies respectively, spring means actuating said assemblies to normal position, and a key controlled lever connection for actuating said rocker arms in the other direction in opposition to said spring means.

5. In a typewriting machine, in combination, a frame, a platen carriage assembly pivotally mounted on said frame, a type bar assembly pivotally mounted on said frame, rocking bars pivotally mounted on said frame and pivotally connected to each of said assemblies, and means operatively associated with said rocking bars engageable therewith for pivoting the same in one direction including a resilient connection.

6. In a typewriting machine, in combination, a frame, a platen carriage assembly mounted on said frame, a type bar assembly mounted on said frame, at least one of said assemblies being pivotally mounted, rocking bars pivotally mounted on said frame and pivotally connected to said pivotally mounted assembly, and means operatively associated with said rocking bars engageable therewith for pivoting the same in one direction including a resilient connection.

7. In a typewriting machine, in combination, a frame, a platen carriage assembly pivotally mounted on said frame, a type bar assembly pivotally mounted on said frame, rocking bars pivotally mounted on said frame and pivotally connected to each of said assemblies, and means operatively associated with said rocking bars for pivoting the same in one direction including a pivotally mounted shift key lever adjacent each rocking bar, a member pivotally mounted on each

shift key lever engageable with its respective rocking bar, and spring means biasing each shift key lever and its associated member into a predetermined relationship.

5 8. In a typewriting machine, in combination, a frame, a platen carriage assembly mounted on said frame, a type bar assembly mounted on said frame, at least one of said assemblies being pivotally mounted, rocking bars pivotally mounted

10 on said frame and pivotally connected to said pivotally mounted assembly, and means operatively associated with said rocking bars for pivoting the same in one direction including a pivotally mounted shift key lever adjacent each rocking bar, a member pivotally mounted on each shift key lever engageable with its respective rocking bar, and spring means biasing each shift key lever and its associated member into a predetermined relationship.

15 9. In a typewriting machine, in combination, a frame, a platen carriage assembly pivotally mounted on said frame, a type bar assembly pivotally mounted on said frame, rocking bars pivotally mounted on said frame and pivotally connected to each of said assemblies, at least one of said rocking bars being adjustable, and means operatively associated with said rocking bars engaging therewith for pivoting the same in one direction including a resilient connection.

20 10. In a typewriting machine, in combination, a frame, a platen carriage assembly pivotally mounted on said frame, a type bar assembly pivotally mounted on said frame, rocking bars pivotally mounted on said frame and pivotally connected to both assemblies, each rocking bar having an extension, a shift key lever pivotally mounted on said frame in association with each rocking bar, a bell-crank lever pivotally mounted on each shift key lever including a first arm in

25 a plane with the rocking bar and a second arm normally engaging an edge of the shift key lever, and spring means urging each bell-crank lever into position with its second arm in contact with its shift key lever, said first arm of said bell-crank lever engaging said rocking bar extension to shift said assemblies of said machine upon pivotal movement of said shift key lever.
